UNITED STATES PATENT OFFICE.

GEORGE P. FINDLAY, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

TUBE-FRAME BRACKET.

Application filed December 18, 1926. Serial No. 155,760.

This invention relates to a bracket or hanger for use on yarn tube frames forming part of the equipment of an Axminster carpet loom. These brackets provide bearings for the yarn spools and also provide means by which the tube frames may be detachably connected to the transporting pattern chains.

It is the general object of my invention to improve the construction and operation of the yielding attaching hook by which the bracket is secured to the chain and to improve the mounting thereof on the bracket.

With this general object in view, an important feature of my invention relates to the provision of a hook so mounted that it is capable of slight transverse movement, tending to reduce the strain on the hook and bracket as the tube frame changes its angular position with respect to the pattern chains.

My invention further relates to arrangements and combinations of parts which will be hereinafter set forth and more particularly pointed out in the appended claims.

A preferred form of the invention is shown in the drawings in which

Fig. 1 is a side elevation, partly in section, showing my improved bracket;

30 Fig. 2 is an end elevation of the bracket, looking in the direction of the arrow 2 in Fig. 1;

Fig. 3 is a view similar to Fig. 1, but showing the bracket in detached position;

35 Fig. 4 is a sectional end elevation, taken along the line 4—4 in Fig. 3; and

Fig. 5 is a side elevation of the hook.

Referring to the drawings, I have indicated a tube frame comprising a rectangular hollow tubular member 10 having a tube frame bracket secured in the end thereof by screws 11. The bracket comprises an upright portion 12 having a bearing 13 for a spool S at its upper end. The member 12 also has an offset chain-engaging portion 14 adapted to extend upward between the links of a transporting pattern chain C. The lower end of the member 12 is offset, as indicated at 15, to provide a lower attaching arm for the bracket, and an L-shaped member 16 is welded or otherwise secured to the member 12 to provide an upper attaching arm.

A hook 18 extends upward through a slot 19 in the chain-engaging portion 14 and is

provided with a head 20 having a hook-like portion which engages the chain C when the parts are in operative relation. The lower end 21 of the hook is offset or bent outwardly and is provided with a pivot stud 22 which extends loosely through an opening 23 in the end of the bracket. The stud 22 extends through both members 12 and 16 and is surrounded by a spring 24, held in position on the stud by a washer 25 and cross pin 26. Above the offset portion 21, the bulge of the hook forms a point of rocking contact with the member 12.

At this point the hook is also provided with an opening 28 through which extends a stud 29, firmly secured in the end wall of the bracket. The opening 28 is of such size that the stud 29 does not engage the hook in any position thereof, the stud being provided for engagement by a screw 31 in the clamp 32 by which the tube frame is carried downward to weaving position. If the bracket fails to disengage from the chain C, the arm 32 will be held upward by engagement of the screw 31 with the stud 22, and a suitable stop motion will be put in operation to stop the loom.

The screw 31 also acts to disengage the hook 18 from the chain C by pressing the hook back against the member 12, as clearly shown in Fig. 3. Such movement of the hook is yieldingly resisted by the spring 24, which is thereby placed under increased compression. It will be understood that the stud 22 fits loosely enough in its opening 23 so that this outward and angular movement of the stud is permitted.

In the operation of the loom, the tube frame brackets are transported in every angular position and are frequently swung about the chain sprockets over an arc of 180 degrees. Such angular movement of the tube frames has been found to induce transverse movement of the hook ends 20, which movement has usually been firmly resisted, necessitating a slipping or sliding movement between the hook and the chain and causing unnecessary wear.

With my improved construction, the hook 18 is free to swing between limits about the axis of the stud 22, moving from the full line to the dotted line position shown in Fig. 4. The limits of movement are defined by the side walls of the slot 19. This provision of limited transverse movement

for the upper end of the hook has been found of substantial advantage, as it relieves the structure of unnecessary strain particularly at the point of attachment of the spring to the bracket, and also reduces the wear upon the end 20 of the hook.

Having thus described my invention and the advantages thereof, I do not wish to be limited to the details herein disclosed otherwise than as set forth in the claims, but what I claim is:

1. In a tube frame, a bracket and a chain-engaging hook mounted on said bracket, said hook having a pivot stud with its axis disposed perpendicular to the line of movement of the chain and extending through the end wall of the bracket, and a coil spring encircling said stud within said bracket and held under compression on said stud.
2. In a tube frame, a bracket and a chain-engaging hook mounted on said bracket, said hook having pivotal movement about an axis substantially perpendicular to the path of

travel of the chain and having a rocking movement about a point of engagement of 25 said hook and bracket above said pivotal axis.

3. In a tube frame bracket, a rigid chain-engaging hook having a point of rocking engagement on said bracket and having its lower end offset away from said bracket below said point of engagement, and a spring effective to yieldingly draw said offset lower end toward said bracket.

4. In a tube frame bracket, a rigid chain-engaging hook having a point of rocking engagement on said bracket and having its lower end offset away from said bracket below said point of engagement, and a spring effective to yieldingly draw said offset lower end toward said bracket, said spring being mounted entirely within the tube frame but being removable with the bracket therefrom.

In testimony whereof I have hereunto affixed my signature.

GEORGE P. FINDLAY.
